UNITED STATES PATENT OFFICE.

JOHN COMER, OF OGDEN, UTAH.

BEET-UNLOADING MEANS.

Application filed July 28, 1925. Serial No. 46,594.

To all whom it may concern:

Be it known that I, JOHN COMER, a citizen of the United States, and a resident of Ogden, in the county of Weber and State 5 of Utah, have invented new and useful Improvements in Beet-Unloading Means, of which the following is a specification.

This invention relates to improvements in beet unloading means, as employed at a beet 10 sugar factory, and particularly embodies a novel system for concurrently unloading and directly fluming the beets, from one or more of their railroad transportation cars, into the beet sugar factory, and preferably 15 with a substantially continuous and regulable feeding delivery.

One of the primary objects of the invention is for economical ends generally, in avoidance of the costly construction and 20 use of high-lines, or elevated railroad car trestles, that are equipped with large receiving bins, or walled compartments therebelow, as now customarily practised for the initial dumping and storage of the beets, and 25 the operations in connection with which require much labor and waste of time, more especially when it is desired to deliver the beets from said storage bins to the factory.

Another primary object of the invention 30 is to provide for the more facile fluming of the beets into the factory, both in point of quantity and controlled feed thereof, whereby the delivery into the factory will neither be so fast nor so slow as to cause either congestion or an under supply, which obviously 35 would hamper or retard operations in the handling thereof in the factory.

The foregoing and other objects and advantages, however, as well as the manner 40 of accomplishing the same, will be clearly apparent as incidental to the following disclosure, and with these general outlining remarks, therefore, reference will now be immediately had to the accompanying drawings, illustrating a practical embodiment of 45 the improved apparatus, in which drawings

Figure 1 is a plan view of my improvements, in plural layout assembly and in association with a double trackage, although 50 it will be understood that a single hopper unit might be employed instead of the paired units as shown; and

Figure 2 is a central longitudinal sectional view, taken along the farside track, 55 and also illustrating the disposition of beet transportation cars in association therewith.

The numeral 5 designates the ground level, and 6 indicates a main beet flume that extends transversely underneath the trackage and leads directly into the factory, for 60 floating the beets from the unloading station into the factory, the said flume being provided with a suitable flowing water supply, indicated by an inlet pipe 7.

The numerals 8 and 9 indicate earth-fills 65 or embankments, although they could be in the form of trestle-work, respectively leading to and from a pit surmounting trestle 11, omitted from Figure 1 for the sake of clearness of illustration of other parts, under 70 which trestle 11 the flume 6 transversely extends, and is preferably disposed at a position centrally of said pit. The numeral 10 indicates revetments or concrete retaining walls, for the ends of the earth-fills 75 8—9, which also are the end walls of the aforesaid pit, and 12 and 13 respectively designate the farside and nearside railway tracks which extend along the aforesaid embankments and the pit and flume surmounting trestle 11. It is to be understood, however, that in the use of the word "pit" I merely employ the same for brevity and convenience, and not in the sense of a pit 80 strictly speaking, to convey the idea of a substantial space, underneath the trestle 11 and above the plane of the flume 6, for the reception of an especially formed hopper or hopper units, which will now be described.

In actual practice, it will be obvious that either one or more of these hopper units 90 may be used, although they are preferably employed in endwise juxtaposed discharging pairs, and two of such pairs or four 95 hopper units being shown in the drawings.

Each of the hopper units embodies upstanding side walls 14 and 15 and one end wall 17, the bottom of the hopper providing for a longitudinal opening or slot 16, and the other end of the hopper being unobstructed or open to function as a discharge end. The end wall 17 and the lower portions of the side walls 14 and 15 preferably flare upwardly, and the side walls 14—15 100 preferably extend substantially higher than the end wall 17, or higher than the paired trestles 11, so that these side walls will project upwardly beyond the bottom of the railroad transportation car that is adapted 105 for location therebetween when discharging its beets. To this end, the upper portions 110

of the side walls 14—15, extending above the top of the end wall 17, would preferably be disposed at an angle to their lower flaring portions, or in parallel instead of flaring relation.

At an appropriate distance below the opening 16, of each hopper, there extends an endless conveyer 19, for the full length of the slot 16, and functions as a traveling 10 endwise-discharging bottom for the hopper.

As a matter of practice, these endless conveyer bottoms are preferably of the well known type of double beaded pan conveyers mounted on side roller-chain supports, 15 which reeve over sprocket wheels, but as the specific construction thereof forms no part of the present invention, they are simply shown conventionally as conveyer belts supported on end rollers 20—21 carried by 20 the cross shafts 22—23. These conveyer elements could be a part of the hopper units, by suitably suspending the shafts 22—23 from the hopper body, or the hoppers and the conveyers may be independently 25 mounted, in coaxing relation, in any suitable way.

The open ends of the hoppers at any event, and hence the discharging ends of the conveyers 19, are mounted and disposed in 30 endwise relation with reference to pairs thereof, within the aforesaid pit or enlarged space, adjacently of the beet floating main flume 6 leading to the factory, and the shafts 23 at the discharge ends are preferably employed as the driving shafts for the 35 conveyers, although not necessarily so, the operative surfaces of which conveyers are caused to travel towards said flume, as is apparent from the drawings.

In order that the speed of these traveling bottoms or conveyers may be appropriately regulated, and hence the discharging feed of the beets from any one or all of the cars being unloaded, dependent upon the needs of the factory at any given time, it is desirable that means be employed for the independent operation of each conveyer under individual regulable control. This, obviously, could be provided for in various ways, but for the 45 purpose of an expedient general illustration, and for that purpose only, I have conventionally shown four separate motors 25, say of about seven and one-half horse power, and each of which motors drives one of the 50 shafts 23 through the medium of interposed reduction gearing 26.

Also, at 27, I have simply illustrated conventionally a motor operated drum, or car mover, which through cable means may be 60 employed for hauling the loaded railroad beet transportation cars, either singly or in pairs, into proper unloading position on the trestle-work 11, over a complementary hopper, the numeral 28 designating one of said 65 loaded cars before being hauled into unload-

ing position, the numeral 29 designating two of such cars moved to their unloading positions, and the numeral 30 showing in dotted lines an emptied car started down the inclined track, leading from the trestle 70 11, which track may be of about a one per cent grade, or sufficient to cause an empty car to travel of its own momentum when started.

It is believed that the operations of unloading from the cars and direct fluming of the beets therefrom into the factory will be clearly understood from the drawings and foregoing description, and that it would only be unnecessary description to further 75 enlarge upon the same, but although I have thus fully disclosed my invention, it will be understood that I do not wish to unnecessarily limit myself to all of the features exactly as disclosed, excepting as they may 80 come within the terms of the claims, or equivalents thereof, or as fairly interpreted in the light of the specification if necessary, for it is obvious that some alterations might be made without departing from the spirit 85 of the invention. It may further be said that, although Figure 2 of the drawings shows cross-ties supporting the railroad tracks on the trestle-work 11, these ties could be substituted for by suitably supported 90 longitudinal timbers or stringers for the lengthwise support of the track rails, which would allow for the discharge of the beets from the cars, into the hoppers, without the beets being bruised by striking cross-ties or 95 becoming wedged therebetween.

Having thus fully described my invention, what I claim as new and patentable is:—

1. In beet unloading stations at the factory, embodying trackage for railroad beet transportation cars and a water flume extending from said trackage to the factory, the combination of an endless conveyer disposed in association with said trackage, for the reception of the beet contents from a car on said trackage, and discharging to said flume, and means for driving said endless conveyer.

2. In beet unloading stations at the factory, embodying trackage for railroad beet transportation cars and a water flume extending from said trackage to the factory, the combination of a hopper, having a discharge opening, in association with said trackage for the reception of the beet contents from a car on said trackage, an endless conveyer disposed in association with the discharge opening of said hopper and discharging to said flume, and means for driving said endless conveyer.

3. In beet unloading stations at the factory, embodying trackage for railroad beet transportation cars and a water flume extending from underneath said trackage to

the factory, the combination of a hopper disposed underneath said trackage, which hopper has a bottom opening, an endless conveyer disposed underneath said bottom opening and discharging to said flume, and means for driving said endless conveyer.

4. In beet unloading stations at the factory, embodying trackage for railroad beet transportation cars and a water flume extending from underneath said trackage to the factory, the combination of a hopper disposed underneath said trackage, which hopper has an elongated longitudinal bottom opening and an open end, an endless conveyer extending along underneath said bottom opening and discharging to said flume at the open end of said hopper, and means for driving said endless conveyer.

5. In beet unloading stations at the factory, embodying trackage for railroad beet transportation cars and a water flume extending from underneath said trackage to the factory, the combination of a hopper disposed underneath said trackage, which hopper has an open end, an elongated longitudinal bottom opening, passing through

said open end, and side walls projecting above the sides of said trackage, an endless conveyer extending along underneath said bottom opening and discharging to said flume at the open end of said hopper, and means for driving said endless conveyer.

6. In beet unloading stations at the factory, embodying trackage for railroad beet transportation cars and a water flume extending transversely underneath said trackage and leading to the factory, the combination of a pair of hoppers disposed underneath said trackage on opposite sides of said flume and extending longitudinally of said trackage, each of said hoppers having an open end located at said flume and an elongated longitudinal bottom opening passing through said open end, an endless conveyer extending along underneath each of said bottom openings and discharging to said flume at the open end of its complementary hopper, and means for driving said conveyers.

In testimony whereof, I affix my signature.

JOHN COMER.
